SOFA BED

Albert M. Spound, Los Angeles, Calif.

Application March 22, 1954, Serial No. 29,636

Term of patent 3½ years

(Cl. D15—11)

To all whom it may concern:

Be known that I, Albert M. Spound, a citizen of the United States, residing at Los Angeles, State of California, have invented a new, original, and ornamental Design for a Sofa Bed, of which the following is a specification, reference being had to the accompanying drawing, forming a part hereof.

Fig. 1 is a front perspective view of a sofa bed showing my new design.

Fig. 2 is a front view of the sofa bed.

Fig. 3 is a rear view of the sofa bed.

Fig. 4 is an end view showing the sofa bed.

I claim:

The ornamental design for a sofa bed, as shown.
